UNITED STATES PATENT OFFICE.

ARTHUR POWELL, OF COBRIDGE, STOKE-ON-TRENT, ENGLAND.

SHOE HEEL.

Application filed October 5, 1920. Serial No. 414,844.

To all whom it may concern:

Be it known that I, ARTHUR POWELL, subject of the King of Great Britain and Ireland, and resident of Cobridge, Stoke-on-Trent, in the county of Stafford, England, manager, have invented certain new and useful Improvements in or Applicable to Shoe Heels, of which the following is a specification.

10 My invention relates to improvements in or applicable to the heels of boots, shoes and other footwear and has particular reference to the type of heels having detachable rubber or composition pads, the object being improved means for enabling the rubber or composition pad to be readily connected to the heel proper of the boot or other footwear and be transferred or renewed when desired, a further object being means for preventing 15 the displacement of the rubber or composition pad during wear.

20 My invention consists essentially in a rubber or composition pad having a projection, tongue, or raised portion thereon provided with an inclined projecting edge to engage a correspondingly shaped groove, bevelled or undercut edge round an open slot in a metal plate fixed on the heel proper of the boot, shoe or other footwear, the said 25 open slotted metal plate having holes or recesses therein to accommodate projections formed on the rubber or composition pad to prevent the displacement thereof when in use.

30 My invention will be fully described with reference to the accompanying drawings in which,

35 Fig. 1 is an elevation of part of a gentleman's boot having my improved detachable heel pad applied thereto,

40 Fig. 2 is an elevation of the heel, shown at Fig. 1, removed from the boot without the detachable rubber or composition pad,

45 Fig. 3 is a plan of Fig. 2.

50 Fig. 4 is a plan of a U shaped metal plate which is fixed to the heel proper of the boot or other footwear and enables the rubber pad to be detachably secured in position and readily removed as desired,

55 Fig. 5 is a section through line A—B of Fig. 4,

60 Fig. 6 is an inverted plan of the detachable rubber or composition pad,

65 Fig. 7 is an elevation of same,

70 Fig. 8 is a section through line C—D of Fig. 6,

Fig. 9 is a back view of the heel of a boot with the detachable rubber or composition pad attached thereto,

75 Fig. 10 is a view of the inside of the heel illustrated at Fig. 9,

Fig. 11 is a similar view to Fig. 4 slightly modified,

80 Fig. 12 is a similar view to Fig. 1 but illustrating a part of a lady's boot having the detachable pad,

Fig. 13 is a back view of Fig. 12,

85 Fig. 14 is a view of the inside of the heel,

Fig. 15 is an inverted plan of the lady's heel illustrated at Fig. 12,

90 Fig. 16 is a plan of a U shaped metal plate which is attached to the lady's heel to carry the detachable rubber or composition pad,

95 Fig. 17 is a cross section through line E—F of Fig. 16, and

100 Fig. 18 is a view of the complete heel as seen from the inside thereof, the sides of the rubber or composition pad being pressed downwards and assuming the position when the pad is being removed from the U shaped metal plate fixed on the heel proper.

105 In these figures *a* is the heel proper and *c* the upper portion of the boot or other footwear, these being of the usual well known construction.

According to my said invention I employ a U shaped metal plate *k* (see plan Fig. 4) which is secured to the heel *a* of the boot or other footwear by screws *m* passing through countersunk holes *n*.

110 The said plate *k* is preferably constructed of aluminum for lightness and has a slot *d* open at its inside *x* as shown at Fig. 4, the edge of the said slot *d* being inclined or bevelled so that when in position on the boot heel it forms an undercut groove *e* extending all round the open slot *d* for the edge *f* of the projection or raised portion *f* of the pad to slide in.

115 To further assist in fixing the detachable rubber pad *b* and to prevent displacement thereof during wear, I employ holes *h* in the U shaped metal plate *k* to accommodate projections *g* (Figs. 6 and 7) formed on the rubber or composition pad *b*.

120 The said holes *h* form recesses when the plate *k* is on the boot heel and if desired such holes may be inclined at *h* and slightly undercut at *h*.

125 To fix the rubber pad *b* in position, the inclined edge *f* of the raised portion or tongue *f* thereon is slid in the direction of

130

135

the arrow Y (Fig. 4) into the open slot d to engage the inclined edge e^2 of the U shaped metal plate, the projections g on the rubber pad then engaging the holes or recesses h^2 in the metal plate.

In some cases a projection j on the back of the rubber pad b (shown dotted at Fig. 6) may be employed to engage a correspondingly shaped recess h^5 in the U shaped plate k (Fig. 11). The recesses h^2 in the metal plate k and the projections g on the rubber pad b may be of any suitable formation to securely lock the parts together.

The U shaped metal plate k constructed as described is secured to the ordinary heel which may be composed of leather, wood or other material.

The rubber or composition pad b may have a layer of canvas p or other suitable material to strengthen the raised portion or tongue f .

The outer or tread portion of the rubber or composition pad b is roughened in any suitable way to prevent slipping.

Rubber or composition pads of various thicknesses may be moulded or shaped to engage the metal U shaped plate when secured to a lady's high heel by which means the height of the heels may be varied as desired.

To facilitate easy insertion, the rubber or composition pad b is gripped by the fingers at its two sides (see Fig. 18) whilst the edge f^2 of the tongue f of the pad is sliding into the undercut groove e^2 of the U shaped plate, the projections g on the pad taking into the

recesses h^2 of the metal plate immediately the sides of the pad b are released. To remove the rubber or composition pad b the sides thereof are pressed until the projections g clear their recesses h^2 in the plate k when the rubber pad is slid out of the open slot d . This enables the pad to be transferred from one boot to the other during wear or a new pad to be substituted when necessary.

What I claim as my invention and desire to secure by Letters Patent is:—

A pad or rubber lift holder for boots and shoes comprising a U-shaped rigid member for attachment to a boot or shoe, the inner edge of which member is beveled, said rigid member having apertures, the walls of which are inclined longitudinally of the member for a distance at the rear edges of said apertures and terminate in walls at right angles to the length of the said member, in combination with a complementary pad or rubber lift having raised portions with beveled sides and end, and studs positioned at the sides of the beveled sides of the pad, the said studs having inclined edges conforming generally to the contour of the walls of the apertures of the first mentioned member and adapted to enter the said apertures.

In testimony whereof I have hereunto set my hand in the presence of two witnesses.

ARTHUR POWELL.

Witnesses:

J. BENTON,
J. H. COPESTAKE.
